Patented June 7, 1966

205,004

AUTOMOBILE TAILLIGHT LENS

Stanley C. Puszka, 41 Clark St., Meriden, Conn.

Filed Feb. 21, 1964, Ser. No. 78,721

Term of patent 14 years

(Cl. D48—32)

FIG. 1

FIG. 2

FIG. 1 is a front elevational view of an automobile taillight lens showing my new design;

FIG. 2 is a view along line 2—2 of FIG. 1.

I claim:

The ornamental design for an automobile taillight lens, substantially as shown.
